Primary Examiner — Kathleen L Jones*Assistant Examiner* — Jasmine L. Comedy(57) **CLAIM**

The ornamental design for a “luminaire”, as shown and described.

DESCRIPTION

FIG. 1 is a perspective view showing my design;

FIG. 2 is another perspective view thereof;

FIG. 3 is detail view of the perforated insert shown in FIG. 1

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The dashed broken lines depict portions of the luminaire forming no part of the claimed design. The dot-dash broken lines in the drawings indicate areas of the figures shown enlarged and form no part of the claim.
